HAND BLINKER-SIGNAL LIGHT

Charles L. Cleek, P.O. Box 2-4275, Los Angeles, Calif.

Filed Sept. 14, 1959, Ser. No. 57,549

Term of patent 14 years

(Cl. D72—1)

FIG. 1.

FIG. 2.

FIG.3.

FIG.4.

FIG.5.

Figure 1 is a front perspective view taken from the bottom and right side of a hand blinker-signal light embodying my new design:

Figure 2 is a rear perspective view taken from the bottom and left side thereof:

Figure 3 is a side elevational view taken from the right side thereof:

Figure 4 is a front elevational view thereof; and Figure 5 is a top plan view thereof.

I claim:

The ornamental design for a hand blinker-signal light, as shown.
